[57] CLAIM

The ornamental design for dresser or similar article, as shown and described.

DESCRIPTION

FIG. 1 is a front elevational view of a dresser or similar article showing my new design;

FIG. 2 is a top plan view thereof;

FIG. 3 is a right end elevational view thereof; and

FIG. 4 is a left end elevational view thereof.

The rear and bottom of the dresser or similar article are substantially plain and unornamented.
